TELEVISION APPARATUS

Aloysius J. Cawley, Pittston, Pa.

Application August 31, 1931, Serial No. 560,394

17 Claims.

(Cl. 178—6)

The invention relates generally to the electrical transmission of images by means of wire or wireless communicating apparatus. More particularly it is concerned with the production of a very compact means of simultaneously receiving and transmitting images in the same image aperture, thus producing a very useful two way television apparatus in which the images received and transmitted are coextensive. The great advantage resulting from this arrangement is that two persons carrying on a two-way television communication appear to be looking directly at each other.

An important object is the use of a single photoelectric cell which is placed behind the scanning disk, while openings or lenses permit the light to pass to the cell. Thus a glow lamp and a lens alternately traverse the image field, and no interference between reception and transmission is possible.

Still another object of the invention is the placing of concave cylindrical lenses in relation to the glow lamps so that their light is concentrated into a bright line at right angles to the axis of the glow tube or lamp. This permits more accurate image reproduction.

Another object is the provision of a modification in which the photoelectric cell is placed in front of the scanning disk and the scanning beam is projected through the image aperture. This modification also gives coextensive images, which are so desirable in two-way telephone and television communication systems.

Other advantages and objects of the arrangements will be apparent from a consideration of the following specification and claims when read in connection with the accompanying drawing wherein the various figures thereof represent in a conventional manner the principles covered by the invention.

Figure 1 is a side elevational view of the apparatus using a single photoelectric cell behind the scanning disk.

Figure 2 is a front elevational view of the apparatus shown in either Figure 1 or Figure 3.

Figure 3 is a side elevational view of a modification using a light projecting means behind the disk and the photoelectric cell in front of the disk.

Figure 4 is a detailed view of the arrangement of the glow lamp and the cylindrical lens for concentrating its light.

Figure 1 illustrates a disk 1 mounted upon a shaft 7 which is rotated by motor 8. Moving exactly with this disk 1 is a commutator 6, whose segments are connected suitably to the glow tubes

such as neon tubes 3 in such manner that only one tube or only one hole or lens or photoelectric cell is in the image field of the frame 5 at any instant. However, as described in my copending application Serial No. 459,369 for Television system, filed June 3, 1930, the tube and the hole or lens may be in the image field at the same time.

The image varied current, if wires are used, or the image varied electric waves, if radio waves are used, is received by the receiver and conveyed to the brushes *c* and *e* by wires *d* and *i*. The commutator acts to supply this current to the particular glow lamp that is traversing the image aperture in frame 5. An electrooptical element is shown at 3. It, however, has just traversed the image aperture, while a hole 4 is shown in the aperture which is receiving the light from the image formed by the lens A of the person or objects in front of the disk 1. However, in the modification in which the elements 4 are lenses, the lens A is not necessary, as each lens then causes a separate image to traverse the aperture of the photoelectric cell 2. This hole 4 or lens permits the light to pass to the large photoelectric cell 2 shown behind the disk 1. Those holes or lenses, similarly to the glow lamps are arranged on the disk in a spiral so that all of the elemental areas of the image are explored successively in the well known manner. The minute image varied current produced in the photoelectric cell 2 is conveyed by the wires *a* and *b* to the transmitter shown as a wireless transmitting station. This current is here amplified and the corresponding electric waves broadcast to the distant stations. Wire transmission may be used, if desired.

Figure 2 is a front view of the apparatus. The disk having alternate holes or lenses and glow lamps spirally arranged is clearly shown. A hole or lens 4 is shown in the aperture of the frame 5. The glow lamp 3 has just left the aperture and is proceeding to the right, while another lamp will enter the aperture from the left as the hole 4 leaves it. The photoelectric cell 2 is shown behind the disk 1, and covers the image field. The image of the observer is formed in the aperture of the frame 5 and the various holes or lenses 4 scan the image area in the well known manner, so that a proper image varied current is produced in the cell 2. The brushes *c* and *e* are shown on "dead" segments of the commutator 6, which indicates that at the instant shown, no glow lamps are illuminated. The lens 4 is traversing the image field and a line of the image is being transmitted. In the next instant, how-

ever, the brushes will have reached a "live" commutator segment and the glow lamp to the left of the frame 5 will become illuminated as it enters the image field of the frame 5. Then a line of the received image will be produced in the frame 5. It will thus be seen that a line of the image to be transmitted is scanned and a line of the received image is constructed in the aperture of the frame alternately. There is absolutely no possibility of interference between transmission and reception. At the center of each glow lamp 3 there is shown a line at right angles to the axis of the lamp or tube. This is intended to indicate that the light of the glow tube has been converged by a cylindrical lens into a sharp, bright line. This cylindrical lens has its axis placed at right angles to the axis of the glow tube such as 3. This is to concentrate the light of the glow lamp to a fine sharp area in order that it might more accurately traverse and delineate the successive elemental areas of the image to be reproduced. The wires *r* and *s* connect the glow tubes 3, whether neon or other to the different commutator segments. The arrangement shown is only one of the many possible. The element 3 is really composed of a glow tube 3 with a cylindrical lens 9 acting to concentrate its light into a sharp line of a length equal to the width of the line which is scanned in the image field. The relation of the lens 9 and the tube 3 is more clearly set forth in Figures 1, 3 and 4.

Figure 3 shows another modification of the invention. C is a source of light which is properly directed by the lens B to cover the image aperture in the frame 5. Its light is transformed into a beam which scans the object o, such as an observer in the well known manner. The light is reflected from the object o into any number of photoelectric cells one of which is shown at 2. Only the hole 4 or lens is in the aperture of the frame 5, the glow tube 3 being out of the aperture as described above. Thus a line of the image to be transmitted will be scanned and its light reflected from the object o will be received by the photoelectric cell 2 and converted into image varied current which is broadcasted by the transmission station to which it is connected by the wires *a* and *b*. After a line has thus been scanned, a glow lamp 3 is connected by the commutator 6 and brushes *c* and *e* to the receiving apparatus in such manner that the lamp 3 receives the image varied current and reproduces a line of the image in the image field of the frame 5. This light is concentrated into a sharp line by the cylindrical lens 9 as already described. A translucent screen may be provided for the reception of the image if desired. Wires *i* and *d* convey the received current to the brushes *c* and *e*. The disk 1, upon which the glow tubes and lenses or apertures are arranged in a spiral line is supported and rotated by shaft 7 of motor 8.

Figure 4 is a detailed view of the arrangement of the glow tube 3 and its concave cylindrical lens 9. The axis of the lens is shown to be placed at right angles to the axis of the glow tube, and it will thus act to concentrate the light of the tube into a sharp, bright line.

This application is a continuation-in-part application of my applications Serial Number 459,369, filed June 3, 1930 for Television system, Serial Number 455,127, filed May 23, 1930 for Television apparatus and Serial Number 50,528, filed August 15, 1925 for Electrooptical system.

It is to be noted that the disks or other rotat-

ing elements at the two stations are not in exact synchronism, although they are in isochronism. They are out of synchronism by an amount equal to the width of the image frame. This is due to the fact that while a lens or aperture is traversing the image frame at one station, a neon tube or other glow lamp or light source is traversing the image area of the frame at the other station.

Instead of the arrangement illustrated in Figure 3, a modification may be adopted in which the light beam is projected through the lenses or holes at one portion of the disk, and after being reflected from the object is received through the lenses or holes at another portion of the disk which coincides with the image frame, and is thence received in a photoelectric cell and converted into image-varied current. This is similar to the apparatus described in the U. S. patent to Jenkins 1,785,262 of December 16, 1930.

It is desirable that the scanning disk 1 be made black in color, as it will then prevent the reflection of the image formed of the persons or objects adjacent the disk.

Obviously, any other type of scanning element may be used, whether cylinder or tape.

Having described my invention, I claim as new and desire to secure by Letters Patent:

1. A two way television process, consisting in supplying an image modulated electric current to a plurality of light sources which singly traverse an image area in order to produce an image by their movement and variation in intensity in accordance with a second image; simultaneously forming an image in said image area; singly and successively, but alternately relative to the passage of said light sources, passing a plurality of light transmitting areas across said image area to permit the passage of light from said image to coat with means for converting light into electricity in order to produce an image-modulated electric current.

2. A two-way television apparatus consisting of an image area, means for forming an optical image of all of the light received from external objects coextensively in said area, means including but one rotatable scanning element associated with said area and influenced by substantially all of the light of said optical image for converting the light of said optical image into corresponding image-varied current and means associated with said area and borne upon said scanning element for converting substantially all of the energy of a second image-varied current into a corresponding optical image coextensively in said area, both of said images being coextensive in said area.

3. A two-way television apparatus consisting of an image area, means associated with said area including but one scanning element for rectilinearly directing a rectilinear scanning light beam undiminished through said area upon the successive elemental areas of an object, the path described by said light beam being substantially coextensive with said area, means for receiving the light reflected from said objects and converting said light into image-varied current and means in the path of said beam and associated with said area and said scanning element for converting an image-varied current received from a distance into a corresponding optical image in and coextensive with said image area.

4. A two-way television apparatus consisting of an image frame, means for forming an optical image in said frame, a moving medium, a plu-

- rality of light transmitting areas and light sources arranged alternately in a spiral on said medium, the distance between said apertures and said light sources being equal to the width of the aperture of said frame, means for actuating said light sources by means of image varied current only while traversing said frame in order that a second image may be reproduced therein, means for converting the light of said optical image traversing said transmitting areas into image-varied current, said elements cooperating to convert said optical image into current and to reproduce said image from image varied current line for line alternately and independently. 10
- 5 5. A scanning element consisting of a rotatable member, a plurality of light sources and light transmitting portions arranged alternately in a spiral on said member. 15
- 10 6. A scanning element consisting of a rotatable member, a plurality of light sources and light transmitting portions arranged alternately in a spiral on said member, the distance between said light sources and said light transmitting portions being equal to the width of the image produced by said element. 20
- 15 7. A scanning element consisting of a movable member, a plurality of light sources and light transmitting portions arranged alternately in image-exploring relationship on said member and means for successively illuminating said light sources when said member is moved. 25
- 20 8. A scanning element consisting of a rotatable member, a plurality of light sources and light transmitting portions arranged alternately in a spiral on said member and means for successively illuminating said light sources as said member is rotated. 30
- 25 9. In a two-way television system the combination of an image area, electro-optical means borne upon but one rotatable scanning element for reproducing a visible image in and coextensive with said area, said image being reproduced from substantially all of the energy of a received image-varied current, means for forming an image of substantially all of the light received from adjacent objects also in and coextensive with said area, and photoelectric means influenced by substantially all of the light of said image associated with said area for converting the light of said image into a transmissible image-varied current in order to reproduce and transmit images coextensively in said image area. 35
- 30 10. In a two-way television system, the combination of an image area, electro-optical means borne upon but one rotatable scanning element for reproducing a visible image from substantially all of the energy of a received image-varied current in and coextensive with said area, means associated with said area for projecting a scanning light beam undiminished through and in a path coextensive with said area upon adjacent objects, said light beam being reflected therefrom and photoelectric means so positioned as to receive said light after reflection to convert said light into a transmissible image-varied current in order to reproduce and transmit images coextensively in said image area. 40
- 35 11. In a two way television system, the combination of a frame, a scanning element in cooperative relation with said frame, a plurality of alternately disposed apertures and light sources arranged in image exploring relation on said scanning element, means associated with said scanning element for supplying a received image-varied current successively to said light sources only when said sources traverse said frame, means for imparting motion to said scanning element, means for transmitting a beam of exploring light through said apertures and said frame upon an object, said light to be reflected therefrom and photoelectric means so positioned as to receive said light after reflection and convert said light into transmissible image-varied current in order to reproduce and transmit images coextensively in said image frame. 45
- 40 12. A two-way scanning element coextensively cooperable with a single image area consisting of a rotatable member, a plurality of light sources and light transmitting portions arranged on said member in independent separate image exploring relation with an identical image area and means for successively illuminating said light sources as said member is rotated. 50
- 45 13. A two-way scanning element coextensively cooperable with a single image area consisting of a rotatable member and a plurality of light sources and light transmitting portions arranged in independent separate image exploring relation with an identical image area on said member. 55
- 50 14. A scanning apparatus consisting of a light source, means for forming and directing a straight beam of light from said source and directing said beam upon objects, a movable scanning element adjacent said light source and said beam forming means, a plurality of light permeable areas arranged in image exploring relation upon said medium and transversely traversing the entire sectional area of said beam in order to cause said beam to impinge upon the successive elemental areas of said objects to be reflected therefrom, a photoelectric element receiving said reflected light and converting said light into image modulated electric current, a plurality of light sources arranged in image exploring relation on said scanning element and also traversing the entire cross sectional area of said beam coextensively with said light permeable areas, said light permeable areas and said light sources being so arranged on said element as to coextensively scan an identical area, and means for supplying said sources with a second image modulated current in order that images may be coextensively received and transmitted. 60
- 55 15. A two-way television apparatus consisting of means for producing and directing a straight beam of light through an image aperture upon objects to be reflected therefrom, means including but one rotatable scanning element for supporting and moving a plurality of light permeable areas coextensively across said aperture and said beam in image exploring relation in order that said beam may be directed upon the successive elemental areas of said objects, means receiving the light reflected from said objects for converting said light into image-modulated current, a plurality of light sources arranged in coextensive image exploring relation of said aperture on said rotatable scanning element and means for supplying a second image modulated current to said light sources as said sources coextensively traverse said image aperture in order that an image may be transmitted and a second image reproduced in said aperture coextensively. 65
- 60 16. A two-way television apparatus consisting of an image area in which an image is coextensively formed therewith, a rotatable scanning element in cooperative relation with said area, a plurality of light permeable areas formed in said rotatable scanning element arranged in coextensive image exploring relation of said area 70
- 65 70 75

and upon said rotatable element, a photoelectric element arranged in cooperative relation with said rotatable scanning element and said light permeable areas to be influenced by the light 5 of said image to convert said light into an image modulated current and means also arranged in coextensive image exploring relation of said image area and borne by said rotatable scanning element for reproducing a second image from a 10 second image modulated current in and coextensive with said image area.

17. A two-way television apparatus consisting of an area through which an exploring beam of light is projected upon objects to be reflected 15 therefrom, means for projecting light through said area, the path of said beam being coextensive with said area, a rotatable scanning element

in cooperative relation with said area, a plurality of light permeable areas arranged in coextensive image exploring relation of said area upon said rotatable scanning element in cooperative relation with said means for projecting light through said area to cause said exploring beam of light to coextensively traverse said area upon said objects to be reflected therefrom, a photoelectric element so disposed as to be influenced by said reflected light and means also 10 arranged in coextensive image exploring relation of said image area and borne by said rotatable scanning element for reproducing a second image from a second image current in and coextensive with said image area. 15

ALOYSIUS J. CAWLEY.
